DESIGN FOR A FORK

Milton E. Johns, Shreveport, La.

Application May 27, 1942, Serial No. 107,025

Term of patent 14 years

To all whom it may concern:

Be it known that I, Milton E. Johns, a citizen of the United States, residing at Shreveport, in the parish of Caddo and State of Louisiana, have invented a new, original, and ornamental Design for a Fork, of which the following is a specification, reference being had to the accompanying drawing, forming part thereof.

Figure 1 is a plan view of a fork showing my new design.

Figure 2 is an edge view thereof, and

Figure 3 is a transverse sectional view taken substantially on the line 3—3 of Figure 1.

I claim:

The ornamental design for a fork, as shown.

MILTON E. JOHNS.
